VALVED FLUID PRESSURE ACCUMULATOR
Jesse D. Langdon, 1 John St., East Rockaway 5, N.Y.
Filed Mar. 14, 1960, Ser. No. 14,733
4 Claims. (Cl. 4—27)

This application is a continuation in part of Ser. No. 852,110, filed November 10, 1959, in turn continuing from Ser. No. 673,815, filed July 24, 1957, now Pat. 2,918,680, December 29, 1959; original application March 29, 1954, Ser. No. 419,213.

The present application also pertains to application August 19, 1957, Ser. No. 678,799; the construction disclosed by the last mentioned application now Pat. 2,915,761, December 8, 1959, is closely related to the disclosure of the present application.

The primary object of this application is to protect inventive disclosure appertaining to timing means to delay the closure of valve means provided to evacuate a reservoir forming the fluid pressure accumulator of the various species of the invention disclosed by the above recited cross references.

This invention is made for the purpose of obtaining the following results:

- (1) Simplified construction.
- (2) Quick opening of the valve for rapid fluid evacuation.
- (3) Delayed closure of the valve permitting atmosphere to enter the accumulation chamber of the reservoir after fluid pressure has been evacuated.
- (4) To permit liquid under pressure to flow thru an inlet and be discharged thru an outlet of greater capacity than the inlet, at one and the same time permitting atmosphere to enter the accumulation chamber by bypassing liquid flowing from the outlet.

(5) The provision of means providing a flow of liquid from the inlet thru the outlet whereby a trap provided for a water-closet is refilled with liquid after a flushing operation induced by liquid flowing from the accumulation chamber.

(6) The utilization of pneumatic pressure built up by liquid under pressure entering the accumulation chamber via the inlet, whereby liquid is urged to gush thru the outlet accordingly when the valve is opened.

(7) To provide auxiliary air inlet means in combination with the liquid inlet whereby egress of fluid thru the inlet is prevented when a negative pressure exists therein.

Other and further objects and purposes will appear during the progress of the specification, as illustrated by the drawing.

The reduction to practice illustrated by the drawing is purely diagrammatic and may be changed within the scope of the claims.

Of the drawing:

The figure of the drawing illustrates a valve fluid pressure accumulator for the containment of air and liquid, comprising, a reservoir 1 having a liquid inlet 2, a combined air inlet and liquid outlet passage 3 of greater capacity than said liquid inlet and adapted to communicate with atmosphere at least part of the time when in active use, a valve casing 4 being inserted into the lower side of and provided with conduit portion 5 projecting downwardly of said reservoir 1, an annular valve seat 6 projecting radially inwardly of said conduit portion 5, a valve member 7 having a downwardly projecting stem 8, an upwardly projecting eyelet 9 and being adapted to rest on valve seat 6, a ring 10 loosely disposed thru eyelet 9 and the lower end of a stem 11 attached to a float 12 and extended downwardly reciprocally thru an opening 13 thru a partition 14 forming the bottom of a cup 15 and communicating with a chamber 16 provided

2

with port means 17 thru the casing wall for communicating between said reservoir 1 and the passage 3 thru conduit 5; valve actuating means being formed by a flanged plunger 18 provided with a stem having a conical end and being reciprocally extended thru the wall of conduit 5, a handle 19 having a flanged end abutting the flange of plunger 18 having its stem surrounded by a resilient member 20, disposed between the wall of conduit 5 and the flange of plunger 18, same being held in operative relationship with handle 19 by cylindrical housing 21 having its outer end flanged radially inward resting against the outer face of the handle flange near its periphery and being attached to the wall of conduit 5. The stem 8 of valve 7 has a lower conical end abutting the conical end of plunger 18, the coniform ends providing a wedging effect giving additional leverage for tipping valve 7 open more easily. Preferably the abutting conical ends of plunger 18 and stem 8 are set off center in axial relationship producing a lateral frictional contact, this feature serves to rotate the valve 7 thereby distributing the wear upon the lower peripheral edge of the valve head against the seat 6 by turning the valve slightly every time the handle 19 is operated.

When the handle 19 is actuated and the valve 7 is opened, the reservoir 1 being filled with fluid under pressure in the shape of air compressed in chamber A above liquid level W, pneumatic pressure in chamber A urges liquid to gush forth from passage 3 much faster than liquid under pressure can enter thru liquid inlet 2, immediately evacuating reservoir 1 of liquid except for the relatively small amount of liquid entering thru inlet 2 and flowing thru passage 3.

The ring 10 thru stem 11, when float 12 is in position O, provides partial closure means for opening 13, delaying closure of valve 7.

The top of cup 15 is located below any possible predetermined minimum liquid level and is therefore filled with liquid when the reservoir is filled. The opening 13 around stem 11 permits slow drainage of liquid retained in the cup 15, said liquid effective to buoy up float 12 to position O when the valve 7 is open, thereby holding the valve 7 in open position after the liquid is evacuated from the reservoir 1, whereupon, atmosphere is permitted to enter reservoir 1 until cup 15 is drained. While the valve 7 is in open position, liquid entering thru inlet 2 flows thru passage 3. During the evacuation of reservoir 1, the weight of the column of, plus the velocity head of liquid projected thru the passage 3 of conduit 5 creates a slight negative pressure in reservoir 1; atmosphere immediately bypassing liquid flowing from inlet 2 and by gravity thru the passage 3 of greater capacity, enters reservoir 1 balancing the pressure therein until the cup 15 is drained, thereby permitting float 12 to drop closing the valve 7; whereupon liquid under pressure rises above and holds valve 7 closed until the accumulation chamber of reservoir 1 is refilled with pressure fluid.

Another feature of the invention is that during the interim when the valve is held open to permit entry of atmosphere, liquid flowing from inlet 2 thru passage 3 will provide liquid to refill the trap of a water-closet if attached thereto.

Additional features illustrated by the drawing include an auxiliary air inlet 22 which is shown as communicating with conduit 5 to provide liquid drain if valve 23 leaks. The air inlet 22 may communicate directly with atmosphere if desired.

It will be noted inlet 2 has its inner end opening spaced from and disposed opposite to the inner end opening of air inlet 22 which is capped by check valve 23 having downwardly projecting retaining legs of greater length than the space between the opposed inner ends of liquid

inlet 2 and air inlet 22, whereby the valve 23 will at all times be held in seating alignment with both inner ends of liquid inlet 2 and air inlet 22.

This construction prevents contaminated fluid from entering the inner end of inlet 2 when a negative pressure exists therein; at which time atmosphere entering reservoir 1 thru air inlet 22 is effective to urge valve 23 upwardly against and close the inner end of liquid inlet 2. It will be noted air inlet 22 terminates slightly below a liquid level below the level of ports 17 where a residual liquid level is effective to minimize noise due to entrance of atmospheric pressure into reservoir 1 via air inlet 22.

Having described the invention, the operation thereof and the new results obtained, the following claims are made:

1. A valved fluid pressure accumulator for air and liquid, comprising a tank provided with a liquid inlet, a valved casing having its upper end inserted into the lower portion of and providing an outlet for said tank normally closed by a tilttable valve member, said outlet being of substantially greater capacity than said liquid inlet to permit atmosphere to bypass liquid flowing thru said inlet to and from said outlet; wherein said outlet projects beyond the lower portion of said tank, a valve seat formed by the inner end of said outlet, a tilttable valve member having a head resting on said valve seat and closing said outlet, the wall of the upper end of said casing projecting into said tank and being ported above said valve seat for communicating between the hollow of said tank and said outlet, a chamber located above the ported portion of said casing and surrounded by an imperforate wall, a cup superimposed upon said chamber, said cup having its bottom provided with an axial orifice communicating with said chamber, said cup located below a predetermined liquid level in said hollow of said tank to permit the cup to fill with liquid, a float in said cup, a stem projecting downwardly from said float and slidably disposed thru the orifice, a restricted annular passage provided by clearance around said stem to permit flow of liquid from said cup into said chamber, the lower end of said stem projecting into said chamber and being loosely joined axially concomitant said tilttable valve member; whereby the combined weight of said float its stem and the valve member will urge said valve member to close said outlet after the accumulated liquid content has been evacuated from said tank and said cup, said restricted annular passage permitting liquid to drain from said cup into said chamber urging said valve member toward its seat, a plunger being slidably disposed thru the outlet wall on a lateral plane with respect to the stem of said valve member and forming actuating means to tilt and open said valve member, thereby permitting liquid under pneumatic pressure accumulated in said tank to gush forth, the weight plus the velocity head of liquid flowing thru said outlet tending to create a momentary negative pressure in said tank, atmosphere entering said tank bypassing the relatively small volume of liquid flowing from said inlet thru said outlet to balance the pressure within said tank prior to the closing of said valve.

2. A device of the nature defined by claim 1, wherein the liquid inlet conduit and an auxiliary air conduit are extended into said reservoir, the inner ends of both conduits having their end openings opposed to one another and being spaced apart, a check valve member normally resting against and closing the inner end of the air inlet, guide means juxtaposed with said check valve for holding said check valve in alignment between the opposed inner ends of the liquid and air inlets at all times; whereby when a negative pressure exists in said liquid inlet, atmospheric pressure effective via said air inlet conduit, urges said check valve against and to close the inner end of said liquid inlet effective to prevent back-

flow of liquid into a conduit connected to said liquid inlet.

3. A valved fluid pressure accumulator for air and liquid, comprising a tank having a liquid inlet, a valve casing inserted into the lower portion of said tank, the lower end of said casing providing an outlet for said tank substantially larger than said liquid inlet the upper portion of said casing projecting into said tank, port means thru the wall of said casing immediately above the inside of said tank, a chamber surrounded by an imperforate wall portion of said casing extended above said port means, cup means surmounting said chamber and disposed below a predetermined liquid level in said tank, float means disposed in said cup and provided with a stem extended downwardly, slidably thru an orifice in the cup bottom, said stem projecting into said chamber, said orifice surrounding an annular passage around said stem communicating between said cup and said chamber, the lower end of said stem being axially aligned with and secured to joining means concomitant the head of a tilttable valve member provided to close said outlet, an axially disposed stem depending from the valve head and extending into said outlet, manual tilting means provided concomitant with the wall of said outlet and the stem of said valve; wherein the upper end of said outlet forms a seat for said tilttable valve located immediately below said port means, said cup being of a height to contain liquid supporting said float to lift the valve head into said chamber; whereby, the valve being closed and said tank filled with an accumulation of air compressed above liquid in the cavity of said tank and cup to a pressure equal to the inlet pressure, when said valve is tilted open, releasing the pressure head above said valve, said float rising in said cup lifts said valve into the chamber above said ports, pneumatic pressure above the liquid effective to quickly evacuate said tank of liquid, liquid remaining in said cup being slowly drained into said chamber via said orifice delaying the closure of said valve until after the liquid content of the tank has been evacuated.

4. A device of the character defined by claim 3; wherein in the depending stem of the valve member is unguided, relatively large and heavy, the lower end of said stem being coniform, a stemmed plunger having a flanged head reciprocally mounted in a housing projecting from the outside of the outlet, said plunger being held in normal position of rest by a resilient member disposed around the plunger stem between the head of the plunger and the outside wall of said outlet, the stem of the plunger slidably disposed thru the outlet wall and provided with a conical terminal end having its apex projecting against the rounded coniform surface of the lower end of the valve stem; whereby pressure against the plunger head will cause its stem to urge said valve stem off center with respect to the axial alignment of said plunger, said valve stem of the tilttable valve being unguided is thrust aside by the impingement of the plunger apex against the rounded coniform surface of the terminal end of said valve stem thereby exerting a frictional stress laterally between the rounded surfaces of the two conical ends tending to rotate the tilttable valve each time said plunger is activated thereby distributing the wear around the valve head periphery contacting the valve seat.
